DESIGN FOR AN AUTOMOBILE TOP RADIO ANTENNA

Paul Guggenheim, Philadelphia, Pa., assignor to
Philadelphia Metal Drying Form Company,
Philadelphia, Pa., a corporation of Pennsyl-
vania

Application January 19, 1938, Serial No. 74,405

Term of patent 14 years

To all whom it may concern:

Be it known that I, Paul Guggenheim, a citizen of the United States and a resident of Philadelphia, county of Philadelphia, State of Pennsylvania, have invented a new, original, and ornamental Design for Automobile Top Radio Antenna, of which the following is a specification, reference being had to the accompanying drawing forming a part thereof, wherein:

Figure 1 is a side elevational view of an automobile top radio antenna, showing my new design;

Figure 2 is a top plan view of the antenna,

a portion thereof being broken away for convenience of illustration;

Figure 3 is a bottom plan view thereof, a portion thereof being broken away for convenience of illustration;

Figure 4 is a perspective view of an end section of the antenna.

I claim:

The ornamental design for an automobile top radio antenna, substantially as shown and described.

PAUL GUGGENHEIM.
